UNITED STATES PATENT OFFICE

JOHN H. DOMKEE, OF WEST HAVEN, CONNECTICUT, ASSIGNOR TO THE WIRE NOVELTY MANUFACTURING COMPANY, OF WEST HAVEN, CONNECTICUT, A CORPORATION OF CONNECTICUT

SLIDE BUCKLE

Application filed September 26, 1931. Serial No. 565,323.

This invention relates to slide buckles used for adjusting the length of looped straps, webbing and the like, without penetrating the material, the invention, while adapted to 5 any bent wire form of slide buckle, is especially adapted to that class of slide buckles made of round wire bent to form a pair of loops connected at one side and free at the opposite sides and having intermediate bar-structure portions integrally extending from the free side of the loops to the connected side thereof.

The objects of the invention are to provide a reversible slide buckle having the strap- 15 gripping upper and lower bars flattened in the plane of the slide buckle and other bars having spaced projections extending along said plane; to provide a slide buckle of the pair of loops type of which the upper and 20 lower horizontal bars are flattened in the plane of the loops, and the intermediate bar-structure is provided with spaced projections extending in opposite directions along said plane; to provide means for securing together 25 the free sides of such a pair of loops; and to provide means for securing the wire ends of the intermediate bar-structure portions to the connected side of the loops. With these and other objects in view as may become apparent 30 from the within disclosures, the invention consists not only of the particular form herein pointed out and illustrated in the drawing, but readily admits of certain modifications within the scope of what hereinafter may be 35 claimed.

While the character of the invention is broad in its application to the art, reference is here made to one illustrative device embodying the invention and illustrated by the 40 accompanying drawing in which the Figure 1 is an upright elevation of the device; the Figure 2 is a cross-section on the line "2-2" of the previous figure; and the Figure 3 is a cross-section on the line "3-3" 45 of the Figure 1; the Figure 4 being an upright elevation of a modified form of device.

The device about to be described is an improvement upon the devices described by the 50 patents numbered 1,810,647 and 1,762,263, issued to your petitioner June 16, 1931, and

June 10, 1930, respectively, on slide buckles of which the intermediate bar-structures are provided with angular formations projecting in planes perpendicular to, and out of, the plane of the buckle. Referring more 55 particularly to the drawing, however, the slide buckle as illustrated is provided with projections formed, not by bending the wire but by pressing spaced portions of the wire to form nubs projecting therefrom and the 60 upper and lower bar-structures are flattened in the plane of the slide buckle. The device is preferably made from a single piece of round wire of which a middle portion provides the integrally connected side 1 of a 65 pair of loops 2 and 3 lying in a common plane and formed by bending both wire end portions in substantially parallel relation to provide the upper and lower horizontal bar-structures 4 and 5, respectively, of the pair 70 of loops 2 and 3, both wire end portions again being bent, but inwardly toward one another, to provide the relatively free sides 6 and 7 of the pair of loops 2 and 3, and both wire end portions again being bent inwardly and substantially parallel with the upper and lower horizontal bar-structures 4 and 5 to leave the 75 free sides 6 and 7 in substantially relative engagement and to provide the intermediate bar-structure portions 8 and 9 separating the 80 pair of loops 2 and 3, the intermediate bar-structure portions 8 and 9 extending across the slide buckle and engaging their extremities 10 and 11, respectively, within the plane of the loops 2 and 3, with the connected side 85 bar 1. At some convenient step in the formation of the slide buckle, as aforesaid, the spaced nubs 12 are pressed out of the metal of the round wire intermediate bar-structure portion 8 so that the nubs 12 project therefrom along the said plane of the loops 2 and 3, and the spaced nubs 13 are pressed out of the metal of the round wire intermediate bar-structure portion 9 so that the nubs 13 project 90 therefrom along said plane in a direction opposite to that of the nubs 12, and the upper and lower horizontal bar-structures 4 and 5 each having an inner edge portion 14 flattened in the said plane of the loops 2 and 3. To prevent accidental or wanton separation 95 100

of the relatively engaging free sides 6 and 7 of the loops 2 and 3, the engaging metal surfaces at the free sides 6 and 7 are united, as at 15, in permanent intimate union, as by welding, brazing or soldering, so that the original character of said metal surfaces cannot be restored by any force effecting the mere separation of the loops 2 and 3 at that place, and the engaging metal surfaces of the extremities 10 and 11 and the connecting side 1 are likewise united in permanent intimate union, as at 16, within the plane of the slide buckle to provide a rigid structure of the aforesaid form that is reversible in the sense that the 15 elevation opposite to that illustrated by the Figure 1 is substantially identical to the elevation as thus illustrated. While the relatively engaging metal surfaces of the loops 2 and 3 at their free sides 6 and 7, and the engaging metal surfaces of the extremities 10 and 11 of the intermediate bar-structure portions 8 and 9 and the connecting side bar 1, are illustrated and described as preferably being united in permanent intimate union, these engaging parts of the device each may 25 be relatively secured, if desired, in any less permanent and intimate manner.

In use, a strap 17 may be threaded into the slide buckle as illustrated by the Figure 2 so that the flattened inner edges of the portion 14 of the upper and lower horizontal bar-structures 4 and 5 and the spaced nubs 12 and 13 extend in different directions into the path of the threaded strap 17 to grip the strap from different angles to prevent the slide buckle sliding upon a taut strap threaded therethrough.

The modified form of the device, illustrated by the Figure 4, materially differs from the 40 preferred structure only in that the nubs 12' and 13' are provided by an intermediate bar-structure of the one portion 8', and the upper and lower horizontal bar-structures 4' and 5' are flattened throughout, not only their entire 45 length but their entire width as well, but both modified and preferred forms of the device are similar in that they each provide gripping edges and nubs extending in different directions into the path of a strap threaded into the slide buckle, the modified form 50 having engaging metal surfaces, as at 15' and 16' united in permanent intimate union as in the preferred form of the device.

I claim:—

55 1. A slide buckle comprising a piece of wire of uniform diameter throughout its length and bent to form a substantially rectangular frame having side, upper, lower and intermediate bar-structures, the upper and lower bar-structures being flattened in the plane of the frame and the intermediate bar-structure being provided with spaced nubs, each nub being pressed out from said uniform diameter to extend beyond the bar-structure 60 of which a full diameter is maintained be-

tween, and at the rear of, said nubs, said nubs extending in opposite directions along said plane and cooperating with the inner edges of the flattened bar-structures to grip a strap 70 threaded into the slide buckle.

2. A slide buckle comprising a piece of wire of uniform diameter throughout its length and bent to form a pair of loops in a common plane, the loops being integrally connected at one side and free, but engaging one 75 with the other, at the opposite sides, intermediate bar-structure portions integrally extending from the free sides to engage their extremities with the connected side, the upper and lower bar-structures being flattened 80 in the plane of the frame and the intermediate bar-structure portions being provided with spaced nubs, each nub being pressed out from said uniform diameter to extend beyond said portions of which a full diameter is maintained 85 between, and at the rear of said nubs, said nubs extending along said plane in opposite directions and cooperating with the inner edges of the flattened bar-structures to grip a strap threaded into the slide buckle, means 90 uniting in permanent intimate union the engaging metal surfaces of the free sides of the loops, and means likewise uniting the engaging metal surfaces of the extremities with the metal surface of the integrally connected side 95 of the loops.
